The ornamental design for a camera, as shown and described.

DESCRIPTION

FIG. 1 is an exploded top, front and right side perspective view of a camera showing our new design, with a mount disclosed in broken lines to illustrate an environment; FIG. 2 is a top, front, and left side perspective view thereof, shown with the mount omitted;

FIG. 3 is a top, front, and right side perspective view thereof; FIG. 4 is a top plan view thereof;

FIG. 5 is a bottom plan view thereof;

FIG. 6 is a front elevational view thereof;

FIG. 7 is a rear elevational view thereof;

FIG. 8 is a left side elevational view thereof; and,

FIG. 9 is a right side elevational view thereof.

The broken lines depict portions of a camera in which the design is embodied that form no part of the claimed design. The broken lines showing a mount in FIG. 1 represent environmental structure and form no part of the claimed design.
